UNITED STATES PATENT OFFICE.

FRANK W. WICHT, OF BROOKLYN, NEW YORK, ASSIGNOR TO JOSEPH WETTER & CO., OF SAME PLACE.

NUMBERING-HEAD.

SPECIFICATION forming part of Letters Patent No. 391,289, dated October 16, 1885.

Application filed December 5, 1887. Serial No. 256,971. (No model.)

To all whom it may concern:

Be it known that I, FRANK W. WICHT, of the city of Brooklyn, in the county of Kings and State of New York, have invented certain new and useful Improvements in Consecutive-Numbering Machines; and I do hereby declare that the following is a full and exact description thereof, reference being had to the accompanying drawings, and to the letters of reference marked thereon, making a part of specification, in which—

Figure 1 is a plan view of my improved consecutive-numbering head; Fig. 2, a vertical section through one end of the case in line *w w* of Fig. 1; Fig. 3, a vertical section through the plunger in line *x x* of Fig. 2; Fig. 4, a vertical section in line *y y* of Fig. 1, illustrating the swinging frame, and in dotted lines the connection of the plunger therewith; Fig. 5, a vertical section in line *z z* of Fig. 1, illustrating the device for permitting the cipher-type to drop out of line of print, Figs. 6 and 7 being views of the type-wheel detached, showing the cipher-type in its different positions. Fig. 8 is a sectional view illustrating a modification in the device, in which the levers actuating the swinging frame are placed next to the frame and inside of the end of the casing.

Similar letters indicate like parts in all of the figures.

My invention relates to that class of consecutive-numbering heads in which the wheels are actuated by a swinging frame moved by a vertically-reciprocating spring-seated plunger, and has for its object to reduce the length of the head, so as to permit the type in the form in which the head is to be used to be brought into close proximity to both the units-wheel and the wheel farthest removed therefrom, and also to provide a simple means for dropping the cipher on each of the numbering-wheels other than the units-wheel without the use of springs or other auxiliary devices.

It consists in the construction and arrangement of parts, hereinafter fully described, whereby the operative plunger in the head is placed in a plane parallel with the axis of the wheels, in proximity to the periphery thereof, and opposite to the swinging frame, and the drop-cipher in the tens and other wheels to

the right of the units-wheel is formed upon a block which is fitted to rest at its inner end upon the fixed axle upon which the wheels are journaled, and to drop, when required, into a peculiar recess cut in the periphery of said axle. 55

The type-bearing numbering-wheels (designated in the accompanying drawings by the numerals 1 2 3, and which are of the customary form and character) are mounted in the usual manner upon a fixed axial shaft, 4, supported and secured at either end in an inclosing frame or case, 5. The units-wheel 1 in the head is actuated to rotate intermittently by means of a pawl, 6, carried by a swinging frame, 7, pivoted to oscillate upon the shaft 4, a device in common use and which, as well as the means for moving in proper order the wheels 2 3 at the right of the units-wheel, is so well known to the art as to need no further description herein. 70

A plunger or movable block, 8, is fitted to have free vertical movement in suitable ways or between guides in the end pieces, 5 5, of the case in front of the wheels 1 2 3 and parallel with the shaft 4. One or more springs, 9 9, are seated under the plunger to bear it up automatically. A pin, 10, is made to project from one or both ends of the plunger, according to the length thereof, through a vertical slot, 11, 80 in the end of the casing, so as to project into a recess or chamber, 12, formed transversely in the end piece, 5. (See Fig. 3.)

The projecting end of the pin 10 is embraced by the forked end of a horizontal lever, 15, 85 whose opposite end is pivoted to the end piece, 5, within the recess 12, as shown in Fig. 2. A second parallel lever, 16, is interposed between the lever 15 and the inner face of the recess 12, and is pivoted at one end to the end piece, 90 5, at a point near to the slot 11, to extend thence toward the pivoted end of the lever 15, and its free end is fitted with a pin, 17, to project inwardly through a second curved slot, 18, in the end piece, 5, and pass into a radial slot, 19, 95 cut in the proximate end piece of the swinging frame 7, as shown in Fig. 4. The two levers are coupled by a pin, *a*, projecting from the one into a horizontal slot in the other at their point of intersection. By this combina- 100

tion and arrangement of pins and levers a slight depression of the plunger 8 will produce the length of stroke required in the oscillating frame 7 to produce a proper action of its pawls 5 upon the numbering-wheels.

The levers 15 and 16 may be made very thin, to occupy very little space and admit of being fitted in a very shallow recess, 12, in the end piece, 5, so that the thickness of the end piece 10 may be reduced to a minimum to allow a close approach of the type placed outside of it to the proximate numbering-wheel on its inner side.

To permit of the imprint of the figures on 15 the units-wheel alone, or on the units-wheel and one or more of the wheels to the right thereof, without an imprint of the cipher on the remaining wheels to the right, the ciphers on the wheels to the right of the units-wheel 20 are each formed upon a block, 20, (see Figs. 5 to 7,) fitted in a radial slot cut in the wheel, and whose lower end, when the type is in line of print, rests upon the stationary shaft 4, about which the wheel revolves. A recess, 25 21, is cut longitudinally in the shaft 4, said recess being formed with a flat horizontal face parallel with the upper face of the type when the latter is in line of print, and with a lateral overhanging face, as shown in the drawings, 30 whose outer edge, 25, terminates about in a vertical plane coinciding with the axis of the shaft and forms an acute re-entrant angle, 22, constituting the inner wall of the recess. A notch or recess, 23, having a re-entrant angle 35 the counterpart of the edge 25 upon the shaft, is formed upon the inner end of the cipher type-block 20, and the extreme end of the block is formed with a curved face. Ordinarily this curved face rests upon the periphery of the 40 shaft, as shown in Fig. 5, and, as the wheel revolves in the direction of the arrow, (see Fig. 5,) the edge 25 of the recess in the shaft will support the block in line of print until the type thereon is carried forward out of line of 45 print and into a position (see Fig. 6) where it will be carried over the recess without liability of automatically dropping therein, the possibility of its dropping accidentally being prevented by its close fit in its seat. When, however, 50 it has thus passed out of line of print and into a position which admits of its dropping into the recess, it may, when required, be readily pushed down onto the flat face of the recess. After it is so pushed down the wheel 55 may be turned back to line of print, and, the projecting edge overhanging the recess in the shaft being carried thereby into the counterpart re-entrant angle of the recess in the end of the type-block, the block will remain in its 60 inner position out of line of print, as shown in Fig. 7. When, however, the wheel is turned forward again, the block, riding upon the shaft, will be automatically moved outward again as its inner end passes away from the 65 recess on the shaft. (See dotted lines in Fig. 7.)

In the use of this numbering-head the type

surrounding it in the form in which it is to be locked may be brought into close proximity to the numbering-wheels at each end of the 70 head, because of the position of the plunger in front of and parallel with the axis of the wheels instead of at one end thereof. In operation the depression of the plunger 8 by the bearing thereon of the platen or cylinder of 75 the printing press in which the form is placed as it closes upon the type to produce an impression therefrom will, by depressing the free end of the long lever 15, produce an impression of the lever 16, pivoted thereto, and thereby actuate the swinging frame 7, engaged by the pin projecting from the free end of said secondary lever 16, the comparatively short movement of the plunger being made thereby to produce the longer swinging movement of 80 the frame required to properly move the numbering-wheels.

Instead of placing the levers 15 and 16 in a recess in the outer face of the end piece, 5, they may be placed on the inner side of said end 90 piece in manner as shown in Fig. 8, the levers in such case being bent to avoid interference with the shaft 4 and the long lever being made to engage the plunger 8 by passing into a recess therein, in manner as illustrated in said 95 Fig. 8.

The inner curved end of the block carrying the cipher on the tens-wheel and the remaining wheels to the right rests upon the periphery of the shaft on which the wheel revolves, 100 and is thereby supported in its outward position. By reason of the fact that the edge which overhangs the recess in the shaft projects across the vertical plane passing through the line of print the block remains supported 105 in its outward position when brought to the line of print; but if it be desired to drop the cipher below said line it is only necessary to turn the wheel slightly forward independently of the others until the inner end of the block 110 is carried beyond said edge, when it may be pushed down into the recess on the shaft, and, as the projecting edge of the recess may then pass into the notch in the end of the block, the 115 wheel may then be turned back to its first position with the cipher depressed and in position to move in unison with the other wheels. When so moved, the inner end of the type-block is thereby carried out of the recess and upon the periphery of the shaft and forced outward again in readiness for print, unless specially pushed in, as above described. 120

I am aware that a movable cipher-bearing block has heretofore been arranged in a numbering-wheel so as to be carried outward into 125 line of print by means of a cam-disk, said disk being placed at one side of the wheel and fixed to the shaft upon which the wheel revolves in position to engage a lateral overhanging pin on the side of the block, as shown in the patent to Bowman, No. 166,681. My invention is an improvement upon said patented device in that it dispenses with an extra disk and key for each wheel and with a pin or stud upon 130

each cipher-block and permits the numbering-wheels to be brought more closely together in the head.

I claim as my invention—

- 5 1. The combination, in a numbering-head, with its casing, its shaft fixed in said casing, the numbering-wheels rotating upon said shaft, the oscillating frame pivoted upon the shaft, and the pawl carried by said frame to actuate the units-wheel, of a spring-seated plunger mounted to reciprocate in a plane parallel with the shaft in proximity to the wheels, a lever pivoted at one end to the end piece of the casing to extend across said end piece and engage the plunger, a second lever pivoted to the same end piece in proximity to the plunger to extend across the end piece and intersect the first lever, a pin at the end of the second lever engaging a radial slot in the swinging 15 frame, and a pin on the one lever engaging a longitudinal slot in the other lever at their
- 10
- 15
- 20

point of intersection, all substantially in the manner and for the purpose herein set forth.

2. The combination, with a numbering-wheel, of a fixed shaft, 4, upon which said 25 wheel revolves, having a longitudinal re-entrant recess formed upon its upper side to present an overhanging edge, 25, and a type-block, 20, fitted to move radially in a recess in said wheel and having a re-entrant notch, 30 23, formed at its inner end to receive the projecting overhanging edge 25 of the longitudinal recess in said fixed shaft, substantially in the manner and for the purpose herein set forth. 35

In testimony whereof I have signed my name to this specification in the presence of two subscribing witnesses.

FRANK W. WICHT.
